GAME APPARATUS

William R. Edgeworth, Chicago, Ill., assignor to
 Rubini Cigar Company, Chicago, Ill., a corporation of Illinois

Application April 20, 1936, Serial No. 75,482

28 Claims. (Cl. 194—9)

This invention relates to game apparatus, and more particularly pertains to such apparatus which is controlled through the intermediation of a token, such as a coin, and has to do with 5 such a game in which dice or similar elements are employed.

The apparatus of the invention is mainly concerned with automatically playing the well known dice game known as "twenty six", which, 10 as a rule, is played by throw of the dice.

The game of "twenty six" as played by hand, comprises the following order of play in scoring.

First a player must choose one or more characters of the dice, of which ten are employed, 15 for his point or points upon which his score or scores are to be determined, the player being allowed to throw the dice thirteen times. After each throw of the dice, the number of same displaying a character chosen by the player is recorded on a score sheet. Then upon completion of the thirteenth throw of the dice, if the total of any point exceeds twenty six, the player wins.

It is one object of the invention to provide such 25 a game apparatus that will automatically play the game as outlined, through the intermediation of a token or coin for each point chosen, and wherein the total or totals of the point or points scored will be registered during the process of the game until thirteen throws of the dice have been effected.

Although the invention is mainly concerned with the game of "twenty six", the invention is not to be so limited because of its adaptability to 35 other dice games, such as the well known "bunco game".

Further, the games may be played with cubes having sides differently colored in place of numerals, because the scoring is determined by the 40 number of times a given character appears on the dice after thirteen throws thereof.

The above objects will become apparent by reference to the accompanying drawings and 45 the specification as follows.

In the drawings:

Fig. 1 is a plan view of the apparatus.

Fig. 2 is a vertical section of the apparatus, as may be taken on the section line 2—2 of 50 Fig. 1.

Fig. 3 is a diagrammatic elevation of the coin control or coin head means of the apparatus, as may be taken on the line 3—3 of Fig. 2, showing certain parts in full lines and other parts 55 in dot and dash lines.

Fig. 4 is a detail section taken on the line 4—4 of Fig. 3.

Fig. 5 is a detail section taken on the line 5—5 of Fig. 3.

Fig. 6 is a detail plan section of certain parts 5 of Fig. 3, as may be taken on the section line 6—6 of said figure.

Fig. 7 is a detail plan view of the apparatus, with parts broken away, parts in section and other parts shown diagrammatically.

10

Fig. 8 is a vertical detail section of the apparatus, as may be taken substantially on the section line 8—8 of Fig. 7.

15

Fig. 9 is a perspective view of a die employed in the game apparatus.

Fig. 10 is a detail section of the die, as taken on the section line 10—10 of Fig. 9.

Fig. 11 is a detail section of the die, as taken on the section line 11—11 of Fig. 9.

Fig. 12 is another detail section of the die, 20 as taken on the section line 12—12 of Fig. 9.

Fig. 13 is a diagrammatic plan section of Fig. 8, as taken substantially on the section line 13—13 of said figure with parts omitted, parts broken away and other parts shown in diagram 25 and in changed position.

Fig. 14 is a detail view of a portion of Fig. 7, showing certain parts in full and other parts in changed position.

Fig. 15 is a detail vertical section of Fig. 13, 30 as taken substantially on the section line 15—15 of said figure.

Fig. 16 is a circuit diagram of electrically operated means of the invention.

The apparatus includes a box-like housing 1, 35 whose top 2 has a depressed portion 3 forming an enclosure 4 with the glass top cover 5, within which enclosure ten dice 6 are confined to be automatically played. In the depressed portion 3 of the top is a circular opening 7, within which 40 is arranged to rotate, a turn-table or disc 8, which is mounted on the top end of a vertical shaft 9 rotatably mounted in spaced bearings 10 and 11 of a frame-work 12 in the housing. The turn-table is rotated by an electric motor 13 45 (see Fig. 7), whose drive pulley 14 drives a grooved pulley 15 on the turn-table shaft 9, through the intermediation of a belt 16.

The top surface of the turn-table is flush with the top surface of the depressed portion 50 3, and is provided with a fabric covering to cause the dice confined thereon to be tumbled over and over as the table rotates. The dice are confined on the turn-table by annular retaining wall 17, of the depressed portion 3, which is dis- 55

posed concentric with the table and arranged slightly outward of the opening 7 of the depressed portion.

After the dice have been tumbled over on the turn-table for a certain length of time, they are caused to be urged by centrifugal force against the retaining wall 17, and along which wall they are directed into a trap at a given station in cooperative relation with means arranged to register the number of dice displaying a certain character or characters.

The trap includes a segmental arcuate guide wall 18 disposed concentric with and arranged inward of the retaining wall 17, and having brackets 19 at its ends secured to said wall for mounting. The trap may also include a glass top secured under the brackets 19. Gate means is provided for the trap, which is arranged to control the entrance "A" and exit or outlet "B" thereof, whereby the entrance is closed and the exit open during a given number of turns of the turn-table so that the dice may be sufficiently tumbled on the turn-table before they are caused to enter the trap. Upon being so tumbled, the dice are caused to enter the trap upon opening of the entrance thereof, at which time the exit of the trap is closed. The gate comprises an arcuate gate lever 20 disposed outside of the portion of the retaining wall 17 adjacent the trap, and is mounted at its central portion on the top end of a vertical shaft 21 suitably mounted in bearings of the frame-work 12. At one end of the lever 20 is an entrance gate portion 22, in the form of a pointed hook, that is caused to project through a slot 23 in the wall 17 to close the entrance of the trap when the gate lever is turned counter-clockwise, as seen in plan. At the other end of the gate lever is an exit gate portion 24, in the form of a hook, that is caused to project through the slot 23 in the wall 17 to close the exit of the trap when the gate lever is moved in a clockwise direction, as seen in plan. Means for operating the gate lever will be described later.

The means for registering the characters displayed on the dice when in the trap, includes the following.

In order that mechanical means may be employed for determining the characters appearing on the dice in the trap, each die (see Figs. 9 to 12,) is provided with an aperture 25 in each side thereof, with the exception of the side thereof displaying the "six", that is of a depth characteristic of the number appearing on the opposite side. In other words, the depths of the apertures will proportionately increase from that indicative of the "two" side of the die to the "six" side.

When the dice are in the trap, they are disposed directly over upright feeler pins 26, respectively, arranged about the edge of the turn-table, which are then caused to project into the apertures of the dice and in turn cause the operation of registering means for recording the characters displayed on the dice.

To this end, the feeler pins are reciprocably mounted in bearings of two vertically spaced upper and lower horizontal support plates 27 and 28, respectively, which are secured by upright posts 28a to the base of the frame-work 12. The lower end of each feeler pin is in slidable pivotal connection with one end of a circuit continuing contact lever 29 which is fulcrumed intermediate its ends, as at 30, on a support post 31, and which lever extends angularly upward toward

the axis of the turn-table with a resilient contactor 32 at its inner end in constant engagement with the periphery of an electric controller drum 33 which is oscillatably mounted on the turntable shaft 9.

Generally, the controller drum 33 is arranged, or provided, with switching means 34 which, upon oscillation of the drum at the proper time, cooperates with electrically operated registering means 35 in recording the number of dice displaying a certain character or characters in the trap, as determined by the position of the feeler pins in the apertures of the dice.

The feeler pins 26 are normally held positively in lowered position, with their top ends slightly below the plane of the top surface of the turn-table, by means of a vertically reciprocable cross-head 36. The cross-head comprises a vertical plate 37, formed arcuately about the axis of the turn-table, with a top flange 38 through which the pins 26 project with a collar 39 on each pin resiliently held against the underside of the flange 38 by a coiled spring 40, which spring is interposed between the collar and the support plate 28. The cross-head plate 37 is mounted for vertical reciprocation upon a vertical guide rod 41 on which the elongated bearing sleeve 42 of the plate is slidably received. The plate 37 is also guided along the arcuate inner edge 43 of the lower support plate 28, whereby it is held in position with respect to the feeler pins. Thus when the cross-head is raised, as seen in Fig. 15, the feeler pins may assume various positions by their engagement with the dice in the trap, and when the cross-head is lowered, all the pins are returned to their normal starting position.

The cross-head is normally held in lowered position by a latch device comprising a latch arm 44 which is loosely fulcrumed on the turn-table shaft 9, below the drum. The latch arm has a hooked end 44a which is guided in a groove of a guide block 45 on the support plate 28, and is arranged to be resiliently urged into a notch 46 in one end of the cross-head plate 37, by means of a tension spring 47. When the latch arm is operated to release the cross-head, in the manner later described, the head is raised by a compression spring 48 which surrounds the guide rod 41 and is interposed between the cross-head sleeve 42 and the base of the rod.

The latch arm 44 is operated to release the cross-head and the cross-head is caused to be returned to its lower position by the following means. Loosely mounted on the turn-table shaft 9 above the drum 33, is an operator arm 50 which is oscillated by a crank device 51, through the connecting link 52, so as to pass back and forth over the contact levers 29. The crank device comprises a gear, suitably mounted to rotate, which is in mesh with, so as to be driven by, the drive pinion 51a on the drive shaft of an electric motor 51b.

As the operator arm 50 is about to complete a stroke in the direction of the latch arm, as seen in Fig. 7, it engages a lug 53 on the latch arm and moves same therewith to release the hooked end 44a thereof from the notch of the cross-head, whereupon the feeler pins are elevated into the dice in the trap. When the cross-head is in its raised position, the latch arm is held in its releasing position by its engagement with the end of the head.

When at the other end of its stroke, as seen in Fig. 14, the operator arm operates upon the cam end 54 of a cross-head control lever 55 which

lowers the cross-head. The lever 55 has sliding connection at its central portion with the cross-head sleeve, as at 56, and is fulcrumed at its end opposite the cam thereon on the lower support plate 28, as at 57.

The operator arm 50 also controls the operation of the gate lever 20 in time relation with the feeler pins 26. To this end, as the operator arm is depressing the cross-head operating lever 55, to lower the feeler pins, as seen in Fig. 14, it also has camming engagement with the cam end 58 of a gate control lever 59 in cooperating therewith to rock the gate lever 20 so that its gate portion 22 is projected across the entrance of the trap, and whereupon its exit gate portion is withdrawn from the exit of the trap. The gate control lever 59 is centrally secured on the gate shaft 21, and has an arm extension 60 opposite its cam end arranged to be engaged by the hooked end 64 of a spring pressed trigger 62, to cooperate therewith in holding the gate lever 20 in its position closing the entrance of the trap against the tension of a tension spring 63 suitably connected with the control lever. The trigger 62 is pivoted, as at 64, on the upper support plate 27, and has a cam arm extension 65 for cooperative engagement with the operator arm 50 to cause the release of the gate lever.

The gate lever 20 remains in its position closing the entrance of the trap while the operator arm is returning toward the other end of its stroke in the direction of the latch arm 44, and just prior to its engagement with the latch arm, the operator arm engages the cam arm 65 of the trigger to release same, whereupon the gate lever is moved by the spring 63 to effect the opening and closing of the entrance and exit of the trap respectively, as seen in Fig. 7.

The controller drum 33 and the registering means 35 controlled thereby as determined by the position of the feeler pins in the dice when same are in the trap, will now be described.

The registering means includes seven similar dial devices 66, 67, 68, 69, 70, 71 and 72, which, with the exception of the last mentioned, are arranged to respectively register the totals relating to the number of dice displaying the "ace", "two", "three", "four", "five" and "six" after each trapping operation of the dice. The dial devices are located in a row directly below the depressed portion 3 of the housing. In the depressed portion 3 of the housing is a suitable total indicating window 72a for each dial device. The dials 66 to 71, inclusive, are arranged with numerals from "0" to "38" preferably. The dial device 72 is adapted to register the number of cycles of operation of the apparatus, and is arranged to cooperate with token or coin control means in maintaining the apparatus operative until thirteen recording operations have been completed.

Each dial device comprises a dial mounted on a suitably supported shaft 73, on which one end of a clock spring 74 is connected with its other end anchored so as to urge the dial in a direction returning same to its starting position with the "0" thereof appearing at its window. Each dial is held in its said position by a stop 75 which limits the movement of a pin 76 on each dial. Each dial is provided with a ratchet wheel 77 thereunder which is operated to advance the dial by a pawl 78 pivotally connected to one end of the sliding core 79 of a solenoid 80. Upon energization of a solenoid, its dial is advanced one step, in which position the dial is held against

the tension of its spring, by a spring pressed holding dog 81 pivoted suitably at 82.

Mounted radially in the insulating section 83 of the controller drum 33, and arranged in spaced relation vertically with contact surfaces flush with the periphery of the drum, are circuit continuing contacts 84, 85, 86, 87, 88 and 89, reading from the upper to the lower, which are respectively in electric circuit connection, through conductors 90, with one side of the solenoids of the dials 66 to 71, which are representative of the "ace" to the "six", respectively, of the dice. The other side of the solenoids of the score recording dials are connected to one side of the power lines 91, from which continues a main conductor 91a having branches 91b connected to the solenoids. The other side of the power lines is grounded to the frame 12 of the apparatus in completing circuit connection to the solenoids as well as to the motors 13 and 51b driving the turn-table and operator arm.

Thus, assuming that there are three dice in the trap showing the "ace", the resilient contactors of the levers 29 operated by the feeler pins, are lowered into the plane of the drum contact 84 representative of the "ace" dial, when the pins are raised into contact with the dice. Then, when the drum is oscillated with the operator arm, in a manner later described, when same returns after releasing the latch arm, said drum contact is caused to engage each of the contactors of the levers 29 successively, whereupon the solenoid of the "ace" dial is energized three times to cause the dial to register "3".

The operator arm is connected with the drum 33, directly above the contacts thereof, by being engaged in a notch 93 in the insulating section 83 of the drum.

Each dial device 66 to 71, inclusive, is rendered operable through deposit of a token or coin in coin controlled means, which also renders the playing apparatus operative until thirteen recording operations of the dice have been completed, or in other words, until the operator arm 59 has completed thirteen oscillations.

Referring to Figs. 1 to 6, the coin controlled means comprises a coin slot head 94 mounted under the top 2 of the housing, and is arranged to extend alongside the row of dial devices. The coin head has six aligned coin slots 95 spaced in accordance with the dial devices 66 to 71, so as to be representative thereof respectively. Each coin slot continues downward to the mid portion of the head, from which point it continues horizontally, as at 96, for a short distance, then again continues downward into an outlet portion 97. Slidably mounted in the side of the coin head are two spaced and interconnected coin actuated bars 98, which intercept one side of the horizontal coin slot portion 96. Slidably mounted between the bars 98 is a coin actuator bar 99 adapted to actuate the bars 98 by way of a coin 99a. When a coin is deposited in a coin slot, it is confined in the portion 96 thereof, and is interposed loosely between a pin 100 on the bar 99 and a pin 101 on each bar 98, whereby, when the bar 99 is advanced, by manual manipulation of its handle 101b, the coin is advanced to a position over the outlet portion of the slot and the bars 98 are in turn advanced thereby with the bar 99. When the coin actuator bar 99 is returned, by means of a suitable tension spring 103 connected therewith, the positioned coin is caused to drop into the exit portion of the slot, and is caused to remain 75

therein for cooperating with switching means in rendering its respective dial device operative. The coin is retained in the slot outlet by its engagement with a stop pin 104 on a spring urged coin retaining bar 105 which is slidably mounted in the side of the coin slot head so as to intercept the outlet, as seen in Fig. 3.

The switching means for cooperating with a coin in the outlet of a slot includes the following.

Extending along the side of the coin slot head, and arranged adjacent a coin actuated bar 98 so as to be operated thereby, is a movable switch-carrier bar 106, which is pivotally mounted to the head, as at 107, so as to swing toward or away from the head. On the carrier bar are mounted six switches 108 included in the conductors 91b of the solenoids of the dice recording dials respectively, and each of which is arranged to cooperate with a coin in the outlet of a slot in completing the circuit to its respective dial device solenoid, when the carrier bar is moved toward the coin head, and which movement of the carrier is effected by the coin actuated bars 98 when same are retracted.

Each switch 108 includes two adjacent normally spaced leaf spring contact members 108a and 108b which depend from the carrier with a coin contactor 111, of insulating material, on the end of the member 108b for projecting through an aperture 112 in the side of the outlet of its respective coin slot for engaging a coin therein, in causing the members to contact and close the circuit to their respective solenoid when the carrier is swung toward the head.

The carrier bar is normally held against the side of the coin head by means of a tension spring 113 suitably connected therewith, and the carrier is moved away from the head in opening the switches 108, by means of its camming engagement with a suitably formed cam 114 on one of the coin actuated bars 98, when said bars are advanced through intermediation of a coin only.

When the coin actuated bars 98 are about to complete their forward strokes, the connecting member 115 at the ends thereof causes the opening of a normally closed switch 116 included in the main conductor 91a between its branches 91b and its power line connection, whereby all the electrically operated devices of the game apparatus are rendered inoperative when a coin is being deposited in the outlet of a coin slot. The said switch 116 is of a type similar to the switches 108, with the exception that the contact members are normally in contact, with one being extended for engagement with the end of the member 115, in causing separation thereof.

The cycle recording dial device 72, generally described in the foregoing, is operably connected with the latch arm 44 and the motors 13 and 51b, to respectively record the number of cycles of operation of the operator arm 50 until thirteen cycles have been completed, and to then open the circuit to the motors in rendering the apparatus inoperative until a coin has been deposited in a slot of the coin slot head, and then deflected by the coin actuator bar into the outlet of the slot.

In that each dice recording operation of the apparatus constitutes what may be termed a shake of the dice, as played by hand, the dial 72 may be termed a shake recording device.

To this end, one side of the solenoid 80 of

the dial 72 is connected by a conductor 117 to one side of a normally open leaf spring switch 118, comprising two adjacent contact members suitably mounted on the lower support plate 28, whose other side is grounded to the frame, as at 119. The other side of said solenoid is connected to a branch 120 of the main conductor 91a, in which branch is a leaf spring switch 121 controlled by the dial device 72.

The switch 118 is so arranged in cooperative relation with the latch arm, as to be closed by engagement therewith when same is released by the operator arm at one end of its stroke, to close the circuit to the solenoid of the shake recording dial in recording the number of strokes of the arm.

When the shake recording dial registers thirteen recording operations of the dice, it causes the switch 121 to open the circuit to the solenoid thereof, whereupon the recording operation ceases and the motors 13 and 51b are rendered inoperative until the introduction of another token or coin in the head 94.

The switch 121 comprises two normally contacting spring contact members, with one arranged to extend into the path of a pin 122 of the dial 72, so as to be actuated thereby in causing the switch to open when the dial records thirteen cycles of operation of the apparatus.

The switch 121 also controls the circuit to the turn-table motor 13, in that one side of the motor is connected to the frame, or ground, and its other side is connected by a conductor 123 to the branch 120 of the main conductor 91a by way of the switch 121.

Circuit connection to the motor 51b, for the operator arm 50, is controlled by the dice in the trap, the gate lever 20 and the switch 121. To this end, one side of the motor 51b is connected to the frame, or ground, and its other side is connected by a conductor 124 to the main power line conductor 91a, by way of the conductor 123 and the switch 121. Included in the conductor 124 is a leaf spring switch 125 mounted on the support plate 27 for controlling the operation of the motor in accordance with the operation of the gate. The switch 125 includes two self closing terminals, of which one is extended into the path of a pin 126 on the gate operating lever 59, so as to be engaged thereby in causing the switch to open when the gate is operated to open the entrance of the trap and close its exit in effecting the trapping of the dice, as seen in Fig. 7.

In that the gate is opened by the release of the trigger 62, effected by the operator arm 50 just prior to its engagement with the latch arm 44, the operator arm will be caused to stop functioning before completing its stroke between its engagement with the trigger and the latch arm, as seen in Fig. 7. The operator arm will remain in this position, about to engage the latch arm, with the entrance of the trap open to receive the dice and the feeler pins lowered, until all of the ten dice are urged by the turn-table into the trap. When the dice are disposed in the trap, they are caused to respectively close ten similar leaf spring switches 127 in series connection in a conductor 128 in bridging connection between the motor conductors 123 and 124, on the motor sides thereof. Thus, when the dice controlled switches have been closed, the electric circuit to the motor 51b is again established to cause the operator arm to complete its stroke in releasing the latch arm to effect projection of the feeler pins into the dice preparatory to the recording thereof. When the

operator arm returns from its engagement with the latch arm, it causes the contacts of the controller drum to cooperate with the resilient contactors 32 of the levers 29 in closing the circuits 5 to the various dial devices as determined by the positions of the feeler pins in the dice, is causing the recording thereof, as heretofore generally described. At the end of its said return stroke, the operator arm again operates the gate lever to close the entrance and open the exit of the trap, and also causes the feeler pins to be lowered, and whereupon the switch 125 is again closed to re-establish circuit to the motor 51b, upon release of the dice from the trap, whereby the operator arm 10 is returned to its starting position preparatory to another cycle of operation.

Each switch 127 is suitably mounted on the depressed top portion 3, at the outer side of that portion of the retaining wall 17 forming the trap, 20 so as to be operated by a die in the trap. Each of these switches includes two normally spaced spring contact members, of which one projects through the slot 23 in the retaining wall and into the trap, so as to be moved into contact with its other member by engagement with its respective die in the trap.

It will be seen that during the time the operator arm 50 is returning from the end of its stroke after causing the release of the dice from the trap, 30 the dice so released onto the turn-table will be constantly deflected from the entrance of the trap by the gate, whereupon they will be tumbled over and over on the table until the entrance of the trap is again opened by the release of the trigger 62.

When the apparatus ceases to function, after thirteen recording operations thereof, as effected by a token or coin in the outlet of a coin slot, the dials are reset to "0" and the coin is released 40 from the slot outlet upon the next operation of the coin actuated bars 98, by way of a coin being deposited into an outlet of a slot. To accomplish this, the lower coin actuated bar 98 has projections 129 which respectively engage the free ends 45 of the dial holding dogs 81, in releasing same from their ratchets of the dials when the bar reaches the end of its forward stroke. When the holding dogs have been released, the dials are urged into their starting positions, back to "0", 50 by their clock springs 74.

The lower coin actuated bar 98 also has a projection 130 which, when the bar is about to reach the end of its forward stroke, engages a pin 131 on the coin retaining slide bar 105, and moves 55 same to cause its pins 104 to be retracted out of the path of a coin in the outlet of a coin slot, and whereupon the released coin is then caused to fall into a suitably arranged container 132 disposed in the housing.

It is, of course, to be understood that the coin actuated bars 98 are retracted after the advancing of a coin into the outlet portion 97 of a coin slot 95 by the coin actuator bar 99 by any suitable means, such as a spring substantially weaker than 60 the spring 103, or a loose connection may be provided between the bars 98 and 99.

It is to be further observed that while the circuit to the operating motors 13 and 51b is broken at the switch 121 upon completion of thirteen 70 cycles of operation of the apparatus, the circuit is closed through the switch 121 when the dials are reset to zero position upon disengagement of the dogs 81 by projections 129 upon advancing movement of bars 98 at the beginning of a new 75 play.

Having thus described my invention, I claim:

1. In a game apparatus, the combination of a plurality of elements formed to be tumbled each having sides provided with different character indicating formations, means inclusive of a playing surface for tumbling the elements over the surface so as to be urged to a given station, trap means at said station to align the elements in order, and means rendered operable by the elements in the trap and arranged to cooperate with certain formations of the elements respectively for registering the totals of the characters indicated thereby. 5

2. The structure as defined in claim 1, wherein the last means comprises electrically operated 15 means having a circuit therefor, and switches included in series connection in the circuit and arranged to be controlled by the elements in the trap respectively.

3. The structure as defined in claim 1, wherein 20 the last means includes an operated registering device for each character, movable feeler members for engagement with formations of the elements in the trap respectively and each arranged whereby it has different limits of movement by engagement with different formations, 25 and each feeler member being operably connected with the devices to operate same respectively in its different limits of movement.

4. In a game apparatus, a plurality of elements 30 formed to be tumbled each having sides provided with different character indicating formations respectively, means inclusive of a playing surface for tumbling the elements over the surface so as to urge same to and from a given station 35 thereof, a trap means at said station for the elements having an entrance and an outlet for the elements with operated gate means arranged to alternately open and close the entrance and outlet respectively, and means arranged to be controlled by the elements in the trap for operating the gate means. 40

5. The structure as defined in claim 4, wherein the last means is arranged to operate the gate means to close the trap entrance and open the 45 outlet after a given time of the trapping of the elements, and including means rendering the operating means inoperative when the gate means is operated to open the trap entrance and close the outlet. 50

6. The structure as defined in claim 4, wherein the last means comprises electrically operated means having a circuit therefor, and switches in said circuit in series connection and arranged to be closed by the elements in the trap respectively. 55

7. The structure as defined in claim 4, wherein the last means is rendered operable by the elements in the trap after a time of the trapping thereof to operate the gate in opening the trap outlet and including means rendering same inoperative when the gate is operated to close the outlet, wherein the operating means includes electrically operated means having a circuit therefor, and a switch in the circuit arranged to be controlled by the gate. 60

8. In a game apparatus of the class described, the combination of means forming a trap for elements formed to be tumbled and then trapped with an entrance opening and an outlet opening, gate means arranged to alternately open and 70 close the entrance and outlet respectively, and operating means for the gate means with means rendering same operable when the elements are in the trap.

9. The structure as defined in claim 8, wherein 75

the operating means includes electrically operated means having circuit therefor, and switches in said circuit in series connection and arranged to be controlled by the elements in the trap.

5 10. The structure as defined in claim 8, including means associated with the operating means for rendering same inoperative when the gate is operated to close the outlet and open the entrance.

10 11. The structure as defined in claim 8, including means associated with the operating means for rendering same inoperative when the gate is operated to close the outlet and open the entrance, wherein the operating means comprises electrically operated means having a circuit therefor, 15 and wherein the means for rendering the operating means inoperative comprises a switch in said circuit arranged to be opened by the gate when same is operated to close the outlet.

20 12. In a game apparatus, the combination of means forming a trap for elements to be tumbled then trapped and having an entrance opening and an outlet opening, gate means arranged to alternately open and close the entrance and outlet respectively, electrically operated operating means for the gate means with a circuit therefor, switches in the circuit arranged to be closed by the elements in the trap in causing the operation of the gate to close the entrance and open the outlet, another switch included in the circuit 25 in bridged relation to the other switches arranged to be closed by the gate upon closing of the entrance for maintaining the operating means operable to cause the opening of the entrance and closing of the outlet and whereby the said switch is opened by the gate upon the opening of the entrance to render the operating means inoperative.

30 13. In a game apparatus, the combination of a plurality of character displaying elements formed to be tumbled and having sides provided with apertures differing in depth to be respectively representative of different characters, means to trap the elements so as to position same in a given order, and means arranged to cooperate with certain apertures of the elements respectively for registering the characters representative thereof, said last means including a reciprocable cross-head, a plurality of feeler pins resiliently mounted on the head and arranged to engage in certain 35 apertures of the elements in the trap upon a movement of the head whereby their limits of movement are determined by the depth of the apertures.

40 14. In a game apparatus, the combination of a character displaying element formed to be tumbled and having sides provided with apertures differing in depth to be respectively representative of different characters, means to trap the element, a registering device for each character, a feeler 45 pin movable into and out of an aperture of the element in the trap, an operator element for the pin arranged to be moved back and forth and operably connected with the pin to effect its said movements at the limits of movement of the operator respectively, and means associated with the operator and pin for establishing an operable connection between the pin and the device of the character represented by the aperture in which the pin is engaged when the operator is moved in 50 one direction of its movement.

55 15. In a game apparatus, the combination of a plurality of character displaying elements adapted to be tumbled and each having sides provided with apertures differing in depth to be respectively 60 representative of different characters, means to

trap the elements in an orderly arrangement, a registering device for each character, feeler pins movable into and out of apertures of the elements in the trap respectively, an operator element for the pins arranged to be moved back and forth between limits and being operably connected with the pins to effect their said movements at said limits respectively, and means associated with the operator and pins for successively establishing operable connections between the pins and the devices of the characters represented by the apertures in which the pins are engaged to cause operation of the devices when the operator is moved in one direction of its movement.

5 10 15 20 25 16. The structure as defined in claim 15, wherein in the trap means comprises means forming an enclosure with open ends providing an entrance and an outlet, operated gate means arranged to alternately open and close the entrance and outlet respectively, and said operator being operably connected to the gate means to cause same to open the outlet at one limit of its movement and to cause same to close the outlet after a given time of its movement from said limit.

17. The structure as defined in claim 15, including means rendered operable by the elements in the trap for operating the operator element.

30 18. The structure as defined in claim 15, wherein in the trap means comprises means forming an enclosure with open ends providing an entrance and an outlet, operated gate means arranged to alternately open and close the entrance and outlet respectively, said operator being operably connected to the gate means to cause same to open the outlet at one limit of its movement and to cause same to close the outlet after a given time of its movement from said limit, and operating means for the operator element with control means rendering same operable when the elements are in the trap and to render same inoperative when the gate means is operated to close the outlet.

35 40 45 50 55 19. In a game apparatus, the combination of a plurality of score registering devices, means for operating the devices from starting positions, the devices having releasable means to restore same to starting positions, a coin slot head having a coin slot for each device with means controlled by a coin when advanced in a slot to render its respective device operable, unitary means for advancing the coins in the slots, and means controlled upon a coin being advanced in a slot for releasing the releasable means of the devices.

60 65 70 75 80 85 90 95 20. In a game apparatus, the combination with an element formed to be tumbled having sides provided with different character indicating means, of operated means inclusive of a playing surface for intermittently causing the element to tumble over the surface whereby it is caused to display a side at intervals, operating means for the operated means, means for registering the number of times a side is displayed including an operated registering device for each character, a coin slot head having a coin slot for each device, and means cooperating with a coin in a slot to control the operation of its respective device and the operating means.

21. The structure as defined in claim 20, wherein in the last means comprises means for cooperating with a coin when advanced in a slot to render its respective device and the operating means operable, and including cycle control means for the operating means arranged to maintain the operating means operable for a given number of said intervals and being arranged to render the de-

vices inoperative after a given number of intervals the element is caused to display a side.

22. In a game apparatus, in combination, a tumblable element having sides provided with different characters, a playing surface for tumbling the element, means for confining the element against movement after having been tumbled, a vertically movable feeler pin, means on the sides of the element representative of the characters on the respective opposite sides for limiting the vertical movement of the feeler pin, indicating means for the characters on the respective sides of the element, and connections between the feeler pin and indicating means for operating the latter in accordance with the vertical position of the feeler pin.

23. In a game apparatus, in combination, a plurality of tumblable elements having sides provided with different characters, a rotatable playing surface for tumbling the elements, a trap for confining the elements after having been tumbled, a plurality of vertically movable feeler pins, means on the sides of the elements representative of the characters on the respective opposite sides for governing the vertical position of the feeler pins when the elements are confined in the trap, an indicator for each of the characters on the elements, electrically operated means including vertically spaced horizontally movable contacts, and circuit closing means operable by the vertically movable feeler pins for effecting operation of the indicators.

24. In a game apparatus, a die provided with an aperture in each of five sides thereof, the apertures varying in depth in accordance with the numbers appearing on the respective opposite sides of the die.

25. In a game apparatus, a plurality of tumblable elements having sides provided with different characters, a rotatable playing surface for tumbling the elements, means for rotating the playing surface, means for periodically confining the elements against tumbling by the rotatable playing surface, an indicator for each of the characters on the elements, means operative by the

elements when confined for effecting operation of the indicators in accordance with the relative positions of the characters thereon, and means for rendering the playing surface operating means inoperative after the elements have been tumbled a predetermined number of times.

26. In a game apparatus, the combination with an element formed to be tumbled having sides provided with different character-indicating means, of operated means inclusive of a playing surface for intermittently causing the element to tumble over the surface whereby it is caused to display a side at intervals, operating means for the operated means, means for registering the number of times a side is displayed including an operated registering device for each character, and selective means to control the operation of the respective devices and the operating means.

27. In a game apparatus, the combination of a plurality of elements each having sides provided with different characters, a motor driven rotatable playing surface for intermittently tumbling the elements, trap means for intermittently restraining the elements, registers operatively associated with the elements when restrained by the trap means for indicating the number of times each of the respective characters is displayed, a cycle register for indicating the number of times the elements have been restrained, a coin slot head having a coin slot for each of the first mentioned registers, means for advancing a coin in any one of the slots, means cooperating with a coin when advanced within any one of the slots for controlling the operation of the respective registers, and means operable by the cycle register for breaking the circuit to the playing surface driving motor when the elements have been restrained a predetermined number of times.

28. The structure defined in claim 27, wherein the coin advancing means includes means for resetting all of the registers to starting position and releasing the last played coin from its slot upon another coin being advanced for a new play.

WILLIAM R. EDGEWORTH. 45
